UNITED STATES PATENT OFFICE.

HARRY C. FOSTER, OF CONNERSVILLE, INDIANA, ASSIGNOR TO INDIANA LAMP COMPANY, OF CONNERSVILLE, INDIANA.

LATCH FOR LAMP CONSTRUCTION.

1,390,773.

Specification of Letters Patent. Patented Sept. 13, 1921.

Application filed July 6, 1920. Serial No. 394,220.

To all whom it may concern:

Be it known that I, HARRY C. FOSTER, a citizen of the United States, and a resident of Connersville, county of Fayette, and State 5 of Indiana, have invented a certain new and useful Latch for Lamp Construction; and I do hereby declare that the following is a full, clear, and exact description thereof, reference being had to the accompanying 10 drawings, in which like numerals refer to like parts.

This invention relates to lamps, and in particular to head lamps or headlights commonly used upon automobiles and the like. 15 The chief object of this invention is to provide means for detachably securing the door or closure member to the lamp casing by simply pushing the door forward on the casing, thus eliminating the necessity of giving it a twist or turn, as is common with such automatic spring locking devices.

The chief feature of the invention consists in providing means associated with the casing flange and door rim which co-operates 20 with each other to yieldingly lock the door to the casing.

Another feature of the invention consists in providing that the locking means, when the detachable members are separated from 30 each other, will be positioned in the receiving position and maintained in said position until such time as the detachable members are again associated with each other.

A further feature of the invention consists 35 in providing the locking means with a pivotally supported U-shaped lever and associating with the same a tripping pin which also serves as a locking pin.

The full nature of this invention will be 40 understood from the accompanying drawings and the following description and claims.

In the drawings Figure 1 is a side elevational view of an automobile headlight 45 embodying the features of the invention and having parts broken away to show other parts in detail, the invention being shown in the locked position. Fig. 2 is a plan view of the invention and associated parts of the 50 headlight. Fig. 3 is a side elevational view of the invention with associated parts of the head lamp with the cover removed and the latching means in the receiving or unlocked position. Fig. 4 is a similar view showing 55 the parts in the inoperative position.

Heretofore it has been the practice to detachably secure a circular door 10 to the circular headlight bowl 11 by providing interlocking means upon said door or closure member and said bowl which co-operate to 60 lock said door to said bowl when said door is moved longitudinally of the bowl axis and circumferentially of said axis. This construction, however, is only applicable to headlamps having circular form. To provide a detachable connection between the door or closure member 10 and the headlight bowl 11 which will be universal so that doors and bowls of geometrical form other than circular, is the chief object of this 65 invention and the main feature thereof. To insure this universality, the attaching means associated with the door 10 and the headlight casing 11 is operable when said detachable members are movable longitudinally of the bowl axis only. With this 70 method of operation head lamps of various geometrical design may be provided with quick detachable doors which will be automatically locked on the casing by simply pushing them thereon.

The embodiment selected to illustrate the invention is shown in the drawings in which 75 10 indicates the door or closure member and 11 the casing, said members being detachably secured together. In the present instance the casing 11 is provided with a forwardly projecting rim or flange 12 and the door is provided with a rearwardly projecting rim 13 which are telescopically arranged. In the present instance the door rim 13 is of larger diameter than the flange 12, although the parts may be reversed if desired. Similarly the invention is applied 80 to the construction illustrated, but it will be also understood that the same may be reversed and the associated parts transferred 85 from one member to the other without departing from the invention.

In the drawings the flange 12 is provided 90 with a transverse longitudinal slot 14 adapted to receive a radially extending pin 15 suitably secured to or carried by the door rim 13. Adjacent the transverse and longitudinally extending slot 14 is a bell crank 100 lever 16 pivoted at 17 and substantially U-shaped in form. One arm of said U-shaped lever is elongated at 18 while the other is provided with a pin member 19 to which is secured a tension member 20, the other end 105 110

of which is secured at 21 to the flange 12. Suitable stop means is associated with the flange 12, and in this instance comprises a lug 22 which limits the tilting movement of the U-shaped lever, as shown clearly in Fig. 3.

When the lever is positioned as shown in Fig. 3 the elongated arm 18 permits the free passage of the pin longitudinally of the 10 bowl rim and into the slot 14. At the same time, said pin engages the inner wall or side 23 of the other lever arm and tilts the lever upon the pivot 17, such that, as said pin moves into the slot, the U-shaped lever also 15 moves inwardly until the elongated end or arm 18 is moved to the position shown in Fig. 1. When in this position the pin 15 is locked against longitudinal movement in said slot, since further longitudinal movement of said pin inwardly is limited by either resting against the bottom of the slot 20 14 or preferably by the closure member 10 engaging upon the casing 11.

The means for retaining said lever in the 25 latching position illustrated in Fig. 1 comprises the tension member 20 which yieldingly retains said latching lever in the locking position, since the tension member is eccentrically secured upon said lever. When 30 the parts are in the position shown in Fig. 3 said tension member maintains the U-shaped lever or bell crank lever 16 in the open or receiving position. The tension member 20 in addition to maintaining the bell crank or U-shaped locking lever in the receiving position, or maintaining the lever 35 in the locking position as shown in Fig. 1, is also adapted to maintain the locking lever 16 in the inoperative position as shown in Fig. 4, should for any reason the bell crank lever accidentally be tilted to the locking position or "over center" without the pin 15 being inserted in said slot. This provision permits the door or closure member 10 40 to be positioned upon the bowl 11, as heretofore described, even though one of the U-shaped levers has been tilted. Said tilted lever thus does not interfere with the normal operation of the detachable members. 45 If desired, suitable stopping means may also limit the tilting movement of the lever as shown in Fig. 4, but in the present instance the bead 24 of the bowl 11 is sufficient, for the lever is pivoted relative thereto such that 50 continued tilting movement of the lever from the locking position is limited in amount only sufficient to position the bell crank clear of the slot. The inoperatively positioned lever may be readily returned to 55 the receiving position by manually tilting the same in the opposite direction.

In the drawings there has been illustrated two telescoping rims, one upon the bowl and the other upon the door, one of said rims being 60 provided with a plurality of longitudi-

nal and transverse slots and the other of said rims being provided with a similar number of radially extending pins, each being seatable in one of said longitudinal and transverse slots and movable longitudinally of 70 the same. In the drawings the locking means illustrated are secured in spaced relation about the periphery of the bowl and the detachable door or closure member.

For further locking the door on the casing, and preventing the movement of the lever 16 to unlocking position, there is provided a latch 25 having a head 26 adapted to engage the arm 18 of the lever as shown in Fig. 1, so as to prevent its opening outwardly. The latch 25 is mounted on a member 27 embedded in the bead 24 so as to be operable therein by the projection 28 extending through a slot. By manually operating the projection 28, the latch 25 will be caused 85 to lock or release the lever 16.

While the invention has been described in detail, many modifications thereof will suggest themselves to those skilled in the art, several of which have been suggested in the foregoing specifications, but said modifications are considered to be within the broad purview of this invention as claimed.

The invention claimed is:

1. A latching device for a lamp construction comprising a rim having a slot therein, a second rim to be latched thereto having a pin receivable by said slot, a U-shaped lever pivotally supported intermediate its axis and adjacent the slot and movable by the pin into position to retain said pin therein, and a spring secured at one end to the end of one of the arms and at the other end to said first mentioned rim, whereby said lever will be yieldingly held in latched or unlatched position thereby.

2. A latching device for a lamp construction including in combination a lamp casing, a detachable closure member for said casing, and locking means movable into the receiving position when the closure member is detached from the casing and movable into the locking position when the closure member is moved longitudinally of the casing axis to seat the member upon and lock the member to the casing.

3. A latching device for a lamp construction including in combination a lamp casing, a detachable closure member for said casing, and locking means movable into the receiving position when the closure member is detached from the casing and movable into the locking position when the closure member is moved longitudinally of the casing axis to seat the member upon and lock the member to the casing, and means for maintaining said locking means in the receiving and locking position.

4. A latching device for a lamp construction comprising a rim having a slot there-

in, a pin receivable by the slot in said rim, a finger pivotally supported adjacent the slot and movable by the pin into position to retain said pin within the slot.

5 5. A latching device for a lamp construction comprising a rim having a slot therein, a pin receivable by the slot in said rim, means pivotally supported adjacent the slot and movable by the pin into position to retain said pin within the slot, and means for yieldingly maintaining said pivoted means in the retaining position.

10 6. A latching device for a lamp construction comprising a slotted rim, a pin receivable by the slot in said rim, a bell crank lever pivotally supported intermediate the ends and adjacent the slot and movable by the pin into position to retain said pin in the slot, and spring means connected to one 15 arm of said lever for maintaining the other arm of said lever adjacent the pin in the retaining position.

15 7. A latching device for a lamp construction comprising a slotted rim, a pin receivable by the slot in said rim, a U-shaped lever with one arm elongated, said lever being pivotally supported intermediate its 20 arms and adjacent the slot and movable by the pin into position to retain said pin in

the slot; spring means associated with the 30 shortened arm of said U-shaped lever, stop means associated with the elongated arm of said lever for limiting the tilting movement of said lever in one direction, and stop means for limiting the tilting movement of 35 said lever in the opposite direction.

8. In a latching device for a lamp construction including a lamp casing and a detachable closure member for said casing, the combination of a rim associated with 40 the casing and a rim associated with the closure member, said rims being telescopically arranged, one of said rims being provided with a slot open at the rim edge, a radially extending pin positioned upon the other rim, being receivable by said slot and movable longitudinally thereof, a locking lever associated with said pin and slot connection for locking said pin in said slot, a latching member mounted within said casing having a portion thereof projecting therethrough for manual control, and a latch mounted on said member in position to engage said lever and prevent it from 45 releasing said pin.

50 In witness whereof, I have hereunto affixed my signature.

55 HARRY C. FOSTER.
